UNITED STATES PATENT OFFICE.

ROBERT T. JOHNSON, OF BIG STONE GAP, VIRGINIA.

CHAIR.

Application filed May 31, 1922. Serial No. 564,954.

To all whom it may concern:

Be it known that I, ROBERT T. JOHNSON, a citizen of the United States, residing at Big Stone Gap, in the county of Wise and State of Virginia, have invented new and useful Improvements in Chairs, of which the following is a specification.

This invention relates to chairs, and has for its chief characteristic the provision of a 10 rocking chair primarily designed for use by infants or children of tender years. The invention aims to provide a chair of this character including a hingedly mounted panel, capable of being arranged in a position 15 to prevent the occupant of the chair from falling out, while the chair is constructed to be quickly and easily converted into a crib, the crib occupying a position at a right angle to the runners of the chair, so 20 that the weight of the crib is equally distributed and properly balanced.

The nature and advantages of the invention will be better understood when the following detailed description is read in connection with the accompanying drawings, the invention residing in the construction, combination, and arrangement of parts as 25 claimed.

In the drawings forming part of this application, like numerals of reference indicate similar parts in the several views, and wherein:—

Figure 1 is a side elevation of my device shown in folded position when it may be 35 used in the capacity of a chair.

Figure 2 is a view taken at right angles to Figure 1.

Figure 3 is a sectional view taken on line 3—3 of Figure 2.

Figure 4 is a similar view taken on line 4—4 of Figure 1.

Figure 5 shows the device slightly changed so as to provide a chair with a closed front so that it may be occupied by an infant or a 45 child of tender age without fear of accident.

Figure 6 is a sectional view taken longitudinally through Figure 5.

Figure 7 shows the device converted into a crib.

Figure 8 is a sectional view taken longitudinally through Figure 7.

The chair includes a lower section A and an upper section B, the lower section comprising the legs 10 which are connected by 55 the transverse members 11, and which legs

are supported by the rockers or runners 12. These legs also support a stationary bottom 13 upon which the section B of the chair is mounted.

The section B includes a seat support 14 which reposes upon the stationary bottom 13, a back 15, and sides and arm rests 16. The section B is pivoted as at 17 upon the stationary bottom of the section A, so that it can be swung to occupy a position at a 60 right angle to the runners 12 for a purpose to be hereinafter described. The section B carries a pivoted latch 18 which is received by a slot 19 in the said stationary bottom, to hold the sections fixed relatively when 65 the section B is positioned for use with the section A as a rocking chair.

The section B has associated therewith a section C, and this section includes spaced side members 20 which are connected together at their forward ends by a cross piece 21. The side members 20 are formed to provide tongues 22 which slide in grooves 23 formed in the seat support of the section B, so that the section C can be extended to 70 provide a crib in a manner to be hereinafter described. The side members of the section C also include members 24 designed somewhat similar to the arm rests of the section B, to form a continuity thereof when 75 the section C is extended to provide a crib. These members 24 slide in grooves 25 formed on the underside of the arm rests of the section B. A panel 25' is hingedly mounted on the cross piece 21 which connects the side members 20 of the section C, and when the article of furniture is used as 80 a rocking chair, this panel 25' depends from the cross piece 21 and is secured to the adjacent legs of the chair through the instrumentality of hook-like elements 26, which are 85 adapted to engage the pins 27 supported by said legs. The section C supports the seat which includes a fixed section 28 and a movable section 29, the latter being hinged 90 upon the fixed section 28 and of the same area as the latter mentioned section. The section 29 reposes upon the section 28 when the article of furniture is used as a chair, but when it is converted into a crib, the 95 section 29 is swung upon its hinge to form a continuity of the fixed section 28 and reposes upon the seat support of the section B.

When the parts are arranged in the man- 110

ner illustrated in Figure 1, the chair has the general appearance of an ordinary rocking chair, and can be used in this capacity. When an infant or a child of tender years 5 occupies the chair, the panel 25' can be separated from the adjacent legs of the chair, and subsequently swung upon its hinge to occupy the position illustrated in Figures 5 and 6, thereby closing the chair 10 in a manner which will prevent the occupant of the chair from falling out. In order to hold the panel 25' in this position, I provide the members 24 of the section C, with pins 30, which are adapted to be engaged by the 15 hook-like elements 26 carried by the panel 25'. When used as a chair, the section B may be swung upon its pivot to assume different angular positions with relation to the section A, it being only necessary to release the pivoted latch 18 for this purpose.

Now, when it is desired to convert the article of furniture from a chair into a crib, it is only necessary to slide the section C 25 forwardly in advance of the section B, and swing the panel 25' upwardly, securing the same to the members 24 of the section C in a manner above described. The section 29 of the seat is then swung rearwardly to lie 30 in a horizontal plane with the section 28, and together with the latter forms the bottom of the crib. The sections B and C as a unit are then swung upon the pivot 17, so that the crib is arranged at a right angle 35 to the runners 12, and the pivot 17 is so located, that when the crib occupies the position just mentioned, the weight is equally

distributed, or in other words the crib properly balanced.

While it is believed that from the foregoing description, the nature and advantages of the invention will be readily apparent, I desire to have it understood that I do not limit myself to what is herein shown and described, and that such changes 45 may be resorted to when desired as fall within the scope of what is claimed.

What I claim is:—

A chair including a support, a fixed bottom section carried thereby, a movable bottom section arranged on the fixed bottom section and pivotally connected thereto, arm rests carried by the latter, the arm rests being provided with longitudinal grooves in their under faces and the movable bottom 50 section being provided with longitudinal grooves in vertical alinement with the first mentioned grooves, a slideable section including vertical sides, tongues carried by the upper ends thereof and received in the first 55 grooves, tongues carried by the lower end and received in the last mentioned grooves and a pair of hinged panels carried by the slideable section and normally arranged in superposed relation to constitute a seat, one 60 of the panels being capable of being arranged at an incline to constitute a back rest or arranged in a horizontal position when the slideable section is extended to extend parallel to the other panel to provide 65 a bottom for the structure.

In testimony whereof I affix my signature.

ROBERT T. JOHNSON.
